UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

KNITTED GLOVE AND METHOD OF MAKING THE SAME.

Application filed April 8, 1920. Serial No. 372,348.

This invention relates to knitted gloves and to the method of making the same.

An object of the invention is to provide a durable and economically constructed glove composed of two longitudinal sections formed of separate and distinct yarns and united during the knitting operation by seams composed of loops formed from said yarns.

10 The invention consists in the novel construction of the glove and in the method of producing the same, whereby the above object and other objects hereinafter appearing may be attained, as set forth in the following specification and particularly pointed out in the claims, reference being had to the accompanying drawings, wherein I have shown merely for the purposes of illustration forms of gloves embodying this invention.

20 In the drawings:—

Fig. 1 is a front elevation of a glove embodying the essential features of my invention;

25 Fig. 2 is a perspective view of a glove blank from which the glove shown in Fig. 1 is produced;

30 Fig. 3 is a diagram on an exaggerated scale illustrating the preferred method of forming the seam which unites the front and back areas of the glove;

Fig. 4 is a front elevation of a modified form of glove blank; and

35 Fig. 5 is a front elevation of still another form of blank from which a glove embodying my invention may be produced.

40 In the illustrated embodiments of my invention I have shown gloves wherein the front and back hand coverings and the front and back digit coverings are formed from separate and distinct yarns, which coverings are united during the knitting operations by suture seams, so-called, composed of the terminal loops of the knitted 45 courses constituting said coverings. It is within the spirit and scope of my invention to form the glove either by hand or upon any suitable type of machine, and in the present case I follow the latter method, preferably, though not necessarily, employing the type of knitting machine wherein the needle cylinder may be either rotated or reciprocated, although the production of the

55 glove embodying this invention essentially involves only the reciprocatory movements of said needle cylinder; but it is to be distinctly understood that within the scope and spirit of the invention the needle cylinder may be held stationary and the necessary movement be imparted to the cams.

60 The more exposed areas of the gloves, such as the hand and inner surfaces of the fingers, may be and preferably are reinforced or strengthened by using yarns which, within the scope and spirit of this invention, may be of an extra heavy quality or made up of a number of yarns which are entirely knitted into partial courses extending back and forth across the hand and finger strips. I thus do away with the floating yarns always present in reinforced fabric of gloves, stockings and the like, that are knitted upon machines in which the needle cylinder is continuously rotated instead of being reciprocated, as in the present case.

65 Obviously a considerable saving in yarn and in the cost of production will be effected by the elimination of said floating yarns and by dispensing with the extra labor required to remove the same after the knitting of the 70 glove has been completed.

75 I have herein shown the front and back hand coverings united in a seam preferably composed of the distinctive yarns of said front and back coverings which are formed 80 into loops during the knitting operation, and these loops are united in any well known manner to form seams which extend along opposite sides of the glove, said seams embodying the characteristics of the seam employed in so-called split foot hosiery.

85 There are numerous ways in which such a glove may be produced, and I shall in the following specification describe several methods whereby the same may be accomplished. The form of blank used by me in producing the glove illustrated in Figs. 1 and 2, embodies a front hand covering 1, and a similarly shaped back hand covering 2, each of said coverings having integrally 90 formed therewith front and rear digit coverings which compose the first, second, third and fourth fingers 3, 4, 5 and 6 respectively. A thumb 7 may be formed in any suitable manner in connection with the front hand covering 1. Preferably, however, this 95 100 105

thumb is knitted integral with said hand covering in the form of a strip double the length of the thumb and knitted into the courses of the hand of said glove. It is,

5 however, within the broad scope and purpose of my invention that the thumb may be separately knitted and afterward applied to the hand in any suitable way, as to a thumb opening that has been left in the
 10 knitting operation; or a thumb opening may be cut or otherwise formed and a separate thumb secured in proper position to the glove.

I have previously referred to my invention as a glove, yet it is obvious that within the scope and purpose of the invention may be included a mitten and also what may be termed a glove mitten,—that is one wherein a separate digit is formed for the
 15 first finger or the first and second fingers, and the remaining fingers are provided for by a single pocket formation. In any of the forms designated the method of procedure which has to do with my invention will
 20 be the same.

The machine for producing the gloves herein is equipped with two separate, preferably semicircular series of needles, each series being actuated by a separate set of
 25 knitting cams and having independent yarn guides or yarn feeding means. Each movement of the cylinder is substantially more than one-half of a rotation, but said knitting cams are so arranged as not to affect
 30 in any way the needles of the other set, with the exception of the end needles of one of the series, which are sometimes called suture needles.

During each distinct movement of the
 35 needle cylinder, a course of loops will be knitted upon both of said series of needles by their respective cams to form partial or semicircular courses. The terminal loops of
 40 said courses are united during the knitting of said courses to form, in the present instance, at opposite sides of the glove, suture
 45 seams 8 (see Figs. 1 and 3). The loops which form said suture seam 8 preferably consist of alternate terminal loops *a* and *b* respectively, of the sections 1 and 2 of the
 50 fabric, as most clearly shown in Fig. 3, said loops being substantially uniform in size and appearance with the loops of the sections united thereby.

55 For further information concerning the formation of a suture seam, reference may be had to my Patent No. 1,154,169, issued September 21, 1915.

The knitting of the glove is preferably
 60 commenced at the wrist 9 and continues along the wrist and part of the hand to the base of the thumb 7, as indicated by the line 10—10 (see Fig. 1). When this line is
 65 reached, knitting is preferably continued on a small group of needles by means of the

knitting cams for the front hand section needles, the other needles of said series being withdrawn from action but retaining their loops.

A strip of fabric is knitted upon said 70 smaller group of needles, double the length of the thumb, the outer portion or covering 11 of said thumb being preferably knitted first and from yarn similar to that used in knitting the back portion of the glove, while 75 the inner portion 12 of said thumb strip is knitted last and from a heavier or more durable yarn,—that is, a yarn corresponding with the yarn from which the front hand portion 1 and the inner faces of the fingers 80 3, 4, 5 and 6 are constructed. When the line 13—13 is reached in the formation of said thumb strip, the remaining needles, including those of both series of needles, are restored to action and knitting proceeds 85 along the front and rear hand coverings to the line 14—14 indicating the bases of the fingers.

Having reached the line 14—14, the wrist, hand portion and thumb of the glove blank 90 will have been substantially completed, the opposite edges of the front and back hand coverings being united by the suture seams 8, 8, while the opposite edges of the thumb strips 11 and 12 remain unseamed, but are 95 later to be stitched together in the usual well known manner.

Assuming now that the finger portions of the glove are to be formed in accordance with the blank illustrated in Fig. 2, I may 100 proceed on a smaller number of needles than are used in the formation of the hand to knit any one or any two of the finger coverings. In the form under consideration the finger coverings are preferably of finger 105 length, and in single width strips which are later seamed together along opposite edges and at their ends to form the finished fingers, with the exception of the first and fourth fingers which, in the present case, 110 preferably have the outer adjacent edges of the front and the rear strips 15 and 16 of the finger 3 united by a suture seam 17 forming a continuation of the seam 8, and likewise the front strip 18 and the back strip 115 19 of the little finger 6 are united along their outer edges by a suture seam 20 forming a continuation of the seam 8 at that side of the blank.

The order in which the several finger 120 strips are knitted is of no great importance. Preferably, however, I knit the little finger 6 first, and this I do preferably by retiring all of the needles of both semicircular series, except those required to knit the front and rear strips 18 and 19.

The knitting of the little or fourth finger strips is accomplished by reciprocating knitting, the group of needles from one of said 125 semicircular series forming the section 18 of 130

a plurality of partial or semicircular connected courses, while upon corresponding needles of the other series the section 19 is knitted also consisting of partial or semicircular courses and formed from distinct 5 yarn. The inner edge 21 of the section 18 and the inner edge 22 of the section 19 are selvaged edges, while the outer edges of said sections 18 and 19 are united during the knitting 10 of said sections by the suture seam 20 composed of the terminal loops of the courses forming said strips 18 and 19, as illustrated in Fig. 3.

Having completed the little finger sections, I next effect the knitting preferably of the third finger strips, and this I do by employing a portion of the needles of the groups that were used in knitting the strips 18 and 19, and add thereto a predetermined 20 number of other needles, while the remaining needles of the two series are retired from action but retaining their loops.

The effect of using portions of the needles previously employed in knitting the little 25 finger strips is that the strip 18 will overlap the front strip 23 of the third finger 5, and the strip 19 will overlap the back strip 24 of the third finger, said overlapping portions when stitched to the corresponding edges of 30 the other strips of like fingers forming a gusset between the third and fourth fingers as illustrated at 25 (Fig. 1). The front and back strips 26 and 27, respectively, of the second finger are produced in substantially 35 the same manner. That is, certain of the needles employed in knitting the front and back strips 23 and 24 are employed in knitting the strips 26 and 27 in addition to other needles which are brought into operation to 40 cooperate therewith in knitting said strips. The use of portions of the needles employed in knitting the strips 23 and 24 result in the formation of a gusset 28 between said third and second fingers.

45 After completing the strips for the second finger I next proceed to knit the strips 15 and 16 constituting the strips for the first finger 3, and this I do by employing a certain number of needles previously used in 50 knitting the strips 26 and 27, with certain new groups,—and thereby form between said second and first fingers a gusset 29. The needles employed in knitting said strips 15 and 16 are those at the ends of the semicircular 55 series of needles, and these two groups are separated only by a suture needle which is operated in a well known manner to effect the interengagement of the terminal loops of the sections constituting the strips 15 and 16 60 to form, as hereinbefore stated, the suture seam 17.

Having completed the knitting of all of the finger strips I now proceed to complete the formation of the glove by seaming together the opposite edges of the thumb strip,

the inner edges and the ends of the first and fourth fingers, opposite edges of the second and third fingers, and the ends of said second and third fingers, the outer edges of said first and fourth fingers having been united by the 70 suture seam during the knitting of the front and back portions of the glove blank.

The tip of the thumb strip may likewise be stitched to form a rounded end corresponding with the ends of the fingers of the 75 glove.

While I have described the knitting of a left-hand glove, it is obvious that a right-hand glove may be knitted in any of the ways described with reference to the left- 80 hand glove.

It will be obvious that although I have described the desired sequence of knitting the fingers of the glove, it is within the scope and purpose of the invention to vary the 85 sequence. That is, the first finger may be knitted and then the second, third and fourth fingers; or two or more finger strips may be knitted simultaneously,—that is to say, the first and third, or the second and fourth may 90 be knitted together. Instead of beginning the knitting at the wrist, it is obvious that within the scope and purpose of my invention knitting may be started at other places, such as at the ends of the finger strips, reversing the order of knitting the various sections of the glove.

As I have previously stated, the principal object of the invention is to form the glove in two sections of fabric united by suture 100 seams, such as I have represented in diagram at 8 (Fig. 3) and which preferably embody in construction alternate loops *a* and *b* constituting the terminal loops respectively of the sections of fabric 1 and 2.

As a result of this method of manufacture it is possible to produce a glove wherein one section, say the palm of the hand and inner surfaces of the fingers and thumb, may be formed practically without waste from a 110 single heavy yarn or from a number of finer yarns knitted as one, while the backs of said portions may be of lighter or less expensive yarns, thus effecting a considerable saving in cost as well as in the amount of yarn used; the extra amount of labor required to remove floating yarns will be eliminated; the front and back coverings of both fingers and hand may be composed of yarns differing in color as well as in weight; and owing to the 115 number of feeds used the glove may be knitted much faster than is ordinarily the case when operating by reciprocating knitting.

In Fig. 4 I have illustrated another form 125 of glove blank embodying the essential features of my invention. In this form the wrist 30, thumb 31, hand 32 and first and fourth fingers 33 and 34, respectively, are constructed in substantially the same man-

ner as are the corresponding sections of the glove shown in Fig. 1, and the front and back sections thereof are united by suture seams 35, 36.

5 The difference in formation between this and the previous blank lies in the second and third finger strips 37 and 38. These strips, instead of being of finger length, are knitted in strips double the normal length of 10 the fingers, and are integral preferably with the back section 39 of the glove. The extremities 40 and 41 of said strips when the same are doubled substantially at mid length, are preferably stitched to the upper edge 32' 15 of the fabric forming the palm 32 of the glove. Thus in the finished glove a seam will extend from the inner edge of the first finger to the inner edge of the second finger, substantially as disclosed in my copending application Serial No. 252,965, filed September 6, 1918. For further information concerning this type of glove blank, reference may be had to said application.

20 In Fig. 5 I have disclosed still another 25 type of glove blank embodying the essential features of my invention, and wherein the front of the wrist and hand sections 42 and 43 respectively are integrally knit and united by suture seams 44 and 45 with corresponding back sections 46 and 47 of said wrist and hand.

30 I preferably form in the front hand section 43 a thumb strip 48 in substantially the same manner as in the previous cases, although it is to be distinctly understood that within the scope and purpose of the invention this strip may be formed separately and attached thereto, or in any other suitable manner.

40 When knitting of the glove blank has reached the line 49 indicating the base line of the digit strips, all of the needles upon which the front, hand and wrist sections were formed are preferably withdrawn from 45 action and the knitting continues upon the said needles from which the back hand section 47 was knitted, to form the several digit strips 50, 51, 52 and 53, which strips are preferably double the normal length of the 50 fingers and overlap each other sufficiently to provide gussets between the several fingers thereof. The knitting of all of said digit strips does not occur simultaneously, but in any desired sequence, as in previous instances. Preferably I first knit upon a predetermined number of those needles previously used in knitting the back hand section, the first finger strip 50, retiring the remaining needles from action during this operation, said retired needles retaining their loops. Upon completion of the first finger strip 50, I may then, and preferably do, knit the second finger strip 51 upon a portion of the needles employed in knitting the strip 50 so as to form an overlap 54, the other

needles of said first strip being withdrawn from action. After completing the strip 51, I may, and preferably do, knit the strip 52 constituting the third finger strip, and this strip is knitted upon a portion of the 70 needles previously employed in knitting the strip 51 to form the overlap 55 and an additional number of needles sufficient to knit the entire width of said strip. After completion of the strip 52, I may, and preferably do, knit the strip 53 for the little or fourth finger, and this upon portions of the needles previously employed in knitting the strip 52 so as to form the overlap 56.

Having completed the knitting of the four 80 finger strips, the glove blank is complete and only requires the necessary seaming of the digit strips to form a completed glove.

85 One very important advantage in forming a glove blank in two sections united by suture seams at opposite sides of the hand and, in certain cases, along the outer edges of the first and fourth finger strips, is that the palm and inner faces of the fingers may be formed of a more durable yarn than that 90 from which the back portions of the glove are formed, and therefore it will be evident that the several blanks hereinbefore described require different methods of inserting the reinforcing or more durable yarns 95 at the proper places.

100 In the blank illustrated in Fig. 2, there will be practically no change in the yarns from the beginning of the knitting at the end of the wrist, provided knitting starts at this point, until all of the digit strips have been completed, except in the formation of the thumb strip wherein the back or outer portion 11 of said strip is preferably formed of yarn similar to that composing the back of the hand, while the inner portion 12 of said thumb strip will be knitted from the more durable yarn employed in the formation of the palm of the hand and the inner faces of the digit strips.

105 In Fig. 4 the second and third digit strips are shown double length, and as these strips are knit entirely upon the needles forming the back hand strip, it will be necessary 110 when the lower halves of these strips have been knitted to change the yarn from the lighter to the heavier or more durable yarn, so that upon the subsequent doubling of said second and third finger strips, the reinforced or heavier portion will form a continuation 115 of the front hand section.

120 In Fig. 5 the lower halves of the finger strips 50, 51, 52 and 53, may be knitted from the lighter yarns, and at mid length of said strips a change may be made to the heavier 125 grade of yarn.

Having thus described several illustrative embodiments of my invention, I desire it to be understood that although specific terms are employed they are used in a generic and 130

descriptive sense and not for purposes of limitation, the scope of the invention being set forth in the following claims:

1. As an article of manufacture, a knitted glove blank having front and back hand coverings united along opposite edges by a suture seam.

2. As an article of manufacture, a knitted glove blank having front and back hand coverings formed of distinct yarns and united along opposite sides by seams consisting of loops formed from said yarns.

3. As an article of manufacture, a glove blank having front and back hand and digit coverings formed of distinct yarns and united along opposite edges by suture seams formed from said distinct yarns.

4. A knitted glove having integral hand and digit sections, the front and back portions of said sections being formed of distinct yarns and united in seams composed of the terminal loops of said sections.

5. A knitted glove having integral hand and digit sections, the front and back portions of said sections being formed of distinct yarns and united along opposite sides of said sections in seams composed of alternate terminal loops of said front and back sections.

30 6. A knitted glove characterized by the formation from distinct yarns of front and back hand and digit sections consisting of connected partial courses, said sections being united along opposite edges by seams composed of end loops of said partial courses.

40 7. A knitted glove characterized by the formation from two distinct yarns, of front and back hand and digit coverings consisting of partial courses, the terminal loops of one of said coverings alternating with those of the other of said coverings to form seams uniting said coverings.

8. The method of forming a glove which consists in knitting upon separate series of 45 needles, from separate yarns, sections of fabric constituting front and back hand coverings, and in causing the terminal needles of one of said series of needles to effect the interengagement of the terminal loops 50 of said fabric sections to form a seam uniting the edges of said sections.

9. The method of forming a glove which consists in knitting upon separate series of needles, from separate yarns, sections of fabric constituting front and back hand coverings, and in effecting, during the knitting of successive courses of said sections, the interengagement of the terminal loops thereof to form seams uniting said front and back 55 sections, then in knitting selvaged finger strips integral with said front and back hand sections, and in effecting the interengagement of the terminal loops at the outer edges of said finger strips to form seams 60 uniting said outer edges.

10. The method of forming a glove which includes knitting upon separate series of needles, from separate yarns, the front hand covering 1 and back hand covering 2, and in effecting during the knitting of successive 70 courses constituting said coverings, the interengagement of the terminal loops *a* and *b* of said hand coverings, to form suture seams 8, 8, then in knitting integral with said hand coverings a plurality of digit strips, and in 75 subsequently seaming the edges of said digit strips.

11. That method of forming a glove which includes knitting from separate yarns upon separate series of needles, the front hand 80 covering and back hand covering and in effecting, during the knitting of successive courses constituting said coverings, the interengagement of the terminal loops of said hand coverings to form suture seams; then 85 in knitting integral with said front and back hand coverings, a plurality of digit strips constituting the fingers, those digit strips which are to form the front of the fingers being knitted upon one of the series of needles and those digit strips that are to constitute the backs of the fingers being knitted upon the other series of needles and in subsequently seaming the edges of the digit 90 strips.

12. That method of forming a glove which includes knitting upon two separate series of needles from separate yarns, the front hand covering and the back hand covering and in effecting, during the knitting of successive 100 courses constituting said coverings, the interengagement of the terminal loops of said hand coverings to form suture seams; then in knitting integral with said hand coverings a plurality of six digit strips to 105 constitute the finger coverings, two of said digit strips being formed wholly upon one of the series of needles, two of the digit strips being formed wholly upon the other series of needles, and the remaining digit strips being knitted partially upon one of the series and partially upon the other series of needles, and in subsequently seaming the edges of a plurality of said digit strips.

13. As an article of manufacture, a knitted glove having the front or palm portion and the front of the finger sections composed of one yarn, and the back together with the back of the finger sections composed of a different yarn, there being suture seams uniting the palm and back portions and the front and back portions of the first and fourth fingers, said suture seams consisting of wales, the stitches whereof are alternately composed of the yarns of the front and back portions of the glove.

14. As an article of manufacture, a knitted glove having the front or palm portion and the front of the finger sections composed of one yarn, and the back together with the

back of the finger sections composed of a different yarn, there being suture seams uniting the palm and back portions and the front and back portions of the first and 5 fourth fingers, said suture seams consisting of wales, the stitches whereof are alternately composed of the yarns of the front and back

portions of the glove, the other edges of the finger strips being selvaged edges and 10 seamed together.

In testimony whereof, I have signed my name to this specification.

GEORGE P. BOSWORTH.
